HEATER FOR BROODER HOUSES

Leslie E. Doan, Hale, Mo., assignor of forty per cent to Ervin C. Winfrey, Hale, Mo.

Application July 26, 1934, Serial No. 737,125

1 Claim. (Cl. 236—6)

This invention relates to improvements in heaters for brooder houses and pertains particularly to an improved type of thermostatically controlled heater designed for the burning of wood.

In brooder house heaters of the types at present commonly supplied, provision is made for the use of coal or liquid fuel principally and in all such heaters, where solid fuel is to be used, grates are employed for the support of such fuel.

In the present invention, the primary object is to provide a brooder heater which is designed primarily for burning wood, in which no grate is employed for the support of the fuel and the draft is supplied over the top of the fuel instead of from the bottom of the same as in other types of burners.

A further object of the invention is to provide an improved means of thermostatically controlling the top draft for the present brooder fuel burner whereby the fuel will be caused to burn up quickly or be checked in rapid response to changes in the temperature of the atmosphere within the brooder house.

Other objects and advantages of the invention will become apparent as the description of the same proceeds and it is to be understood that the invention is not to be limited by the showing of the drawing forming part of the present application but may be changed or modified so long as such changes or modifications mark no material departure from the salient features of the invention as expressed in the appended claim.

In the drawing:

Figure 1 is a vertical section through a portion of a brooder house showing the structure embodying the present invention therein and partially in section.

Figure 2 is a view in plan of the stove with the hover.

Referring to the drawing wherein like numerals of reference designate corresponding parts throughout the views, the numeral 1 indicates the roof and the numeral 2 the side walls of a conventionally illustrated brooder house in which the present invention is shown. The invention comprises a sheet metal stove having a body 3 preferably of cylindrical design and having a top divided transversely to form the rear fixed portion 4, one edge of which extends transversely of the cylindrical body and which has fixed thereto hinges 5, to which is attached the edge of the other part of the top, which is indicated by the numeral 6 and which is designed to be raised and lowered by means of the handle 7 to facili-

tate the introduction of fuel into the stove and the removal of ashes therefrom. The fixed portion 4 of the stove top has an opening with which is connected a stove pipe 8 of the usual design, which extends upwardly through the roof 1 of the housing in the manner illustrated.

The bottom of the stove is indicated by the numeral 9 and is raised from the bottom of the stove body 1 to form a lower chamber which is filled with sand, ashes, or some other suitable material 10, which will prevent an excessive amount of heat from reaching the underlying floor.

At a point above the bottom 9, preferably approximately 8 in., an opening 11 is formed in the wall of the stove and over this opening is secured one end of a pipe 12, which extends horizontally from the wall of the stove and which, although it may be made of any size and length, is preferably of approximately 2 in. in diameter and 14 in. long when used in association with a stove of approximately 30 in. in height and a diameter of 20 in.

Adjacent the outer end of the pipe 12, which constitutes the air inlet for the stove, a bracket 13 is fixed which extends downwardly and forwardly to terminate in a plane common to the free end of the pipe. Oscillatably attached to the free end of this bracket 13 is a draft door 14, which is adapted to close against the end of the pipe 12 to shut off the flow of air into the stove. This draft door, which is in the form of a flat plate, has an arm extension 15, to which is connected one end of a flexible wire or a chain 16, which extends upwardly and is attached at its other end to one end of the rod or lever 17, which is suspended intermediate its ends from the ceiling of the brooder house by the bracket 18.

To the other end of the lever 17 is attached one end of a flexible wire or chain 19, and supported in any suitable manner below the lower end of this flexible connection is a relatively long horizontally disposed shelf 20. From the under side of the shelf 20 adjacent the end nearest the stove is secured the depending bracket 21 to which is pivotally attached one end of a relatively long lever arm 22, the other end of which has the flexible connection 19 connected therewith. Upon the under side of the shelf 20 adjacent the bracket 21 is suspended a thermostat wafer 23 against the under side of which the lever arm 22 is adapted to contact.

While the structure thus far described will satisfactorily control the temperature of a medium size brooder house through cold weather, when

- the weather is severely cold, the stove 3 may be partially surrounded by a canopy 24 of some suitable non-inflammable material, so that a portion of the heat may be concentrated thereunder for the protection of young chickens during the colder periods of the winter. The canopy 24 may have a portion open or cut away, as illustrated, so that the draft pipe 12 may be reached if necessary, and the placing of fuel in the stove and the removal of ashes therefrom may be accomplished conveniently.
- From the foregoing description, it will be readily apparent that the stove structure described and illustrated may be charged with a substantial amount of fuel of the nature of wood and because of the provision for supplying air to the top of the charge, it will not burn out rapidly when the draft door is open and combustion will take place only very slowly when the draft door is closed. It will thus be seen that such rapidly burning fuel as wood or waste paper may be made to last a much longer period of time than would be the case if it were placed on a grate and supplied with air from beneath.
- When the temperature within the brooder house has reached the desired height, the expansion of the thermostatic wafer 23 will cause a pressure to be exerted downwardly on the lever 22 so that the free end of the lever will be depressed to

oscillate the lever 17 and pull the draft door up to closed position. Upon the contraction of the wafer as the temperature cools, the draft door will fall open of its own weight and at the same time will reversely oscillate the lever 22, thus maintaining it always in contact with the wafer. 5

What is claimed is:—

A draft control for a brooder or other type of stove having a bottom draft opening controlled by a gravity-controlled door, comprising a shelf 10 secured adjacent the stove and having an aperture therethrough, a lever disposed horizontally beneath said shelf and pivotally attached at one end to the under side thereof, the other end of the lever being disposed beneath said opening, a 15 thermostat wafer secured to the underside of the shelf between the same and the lever and engaging the latter, a second lever disposed at an elevation above said shelf, a supporting bracket for said second lever and pivotally connected therewith substantially midway of the ends thereof, a cord connecting one end of the second lever through said shelf aperture with the free end of the first lever, and a cord connecting the other end of the second lever with said door, said door 20 by its tendency to open through the effect of gravity, maintaining said cords taut at all times. 25
